(57) CLAIM

I claim the ornamental design for a suit, as shown and described.

DESCRIPTION

FIG. 1 is a perspective view of a suit showing my new design;

FIG. 2 is a front view thereof;

FIG. 3 is a back view thereof;

FIG. 4 is a side elevation view thereof, the opposite side elevation view being a mirror image thereof;

FIG. 5 is a top view thereof; and,

FIG. 6 is a bottom view thereof.

Where included, the dashed lines in FIGS. 1-4 represent stitching.
